DESIGN FOR A SHOE TREE

Louis W. Reinhardt, Brockton, Mass., assignor to George E. Belcher Company, Stoughton, Mass.,
a corporation of Massachusetts

Application October 15, 1943, Serial No. 111,373

Term of patent 3½ years

(Cl. D7—3)

To all whom it may concern:

Be it known that I, Louis W. Reinhardt, a citizen of the United States, residing at Brockton, county of Plymouth, Commonwealth of Massachusetts, have invented a new, original, and ornamental Design for a Shoe Tree, of which the following is a specification, reference being had to the accompanying drawing, forming part thereof,

Fig. 1 is a side elevation of a shoe tree showing the essential features of my design in full lines. Fig. 2 is a top plan view of the part shown in full lines in Fig. 1, and

Fig. 3 is a section on the line 3—3 of Fig. 1.

I claim:

The ornamental design for a shoe tree, as shown and described.

LOUIS W. REINHARDT.
